UNITED STATES PATENT OFFICE.

EVERETT STUCK, OF SYRACUSE, NEW YORK, ASSIGNOR TO THE O. M. EDWARDS COMPANY, INC., OF SYRACUSE, NEW YORK, A CORPORATION OF NEW YORK.

SECTIONAL CABINET.

1,308,647.

Specification of Letters Patent. Patented July 1, 1919.

Application filed June 13, 1914. Serial No. 844,910.

To all whom it may concern:

Be it known that I, EVERETT STUCK, a citizen of the United States, and a resident of Syracuse, in the county of Onondaga and 5 State of New York, have invented certain new and useful Sectional Cabinets, of which the following is a specification.

This invention relates to sectional cabinets or cases, and particularly to sheet metal 10 filing cabinets, and has for its object a particularly simple and efficient arrangement by which the units of the cabinet are locked together; and the invention consists in the novel features of construction hereinafter 15 set forth and claimed.

In describing this invention, reference is had to the accompanying drawings, in which like characters designate corresponding parts in all the views.

20 Figures 1 and 2 are front and rear elevations, respectively, of four units joined together, Fig. 1 being partly broken away, and a drawer being removed from one of the units.

25 Fig. 3 is a side elevation of two units of this cabinet, the upper unit being shown as partly placed in interlocking relation with the lower unit.

Fig. 4 is an enlarged detail view illustrating 30 the hooks of one unit interlocking with the flange of the lengthwise angle iron bar of the next lower unit.

This sectional cabinet includes, generally, 35 units having means which interlock by a horizontal sliding movement of one unit relatively to the other, and additional means which interlock by a vertical movement after the first means have been interlocked. The means which interlock by a horizontal

40 sliding movement is located at the rear ends of the units and locks one unit with the adjoining unit in the next tier and with the adjoining unit in the next column, but in the same tier when there is more than one 45 column, and the means which interlock by a vertical movement is located at the front ends of the units and holds each unit from horizontal displacement relatively to the unit of the next tier and also relatively to 50 the unit in the next column, but in the same tier when there is more than one column. Said means may also be used to lock the units to suitable bases or to lock caps in position, the bases and caps being practically 55 units.

1 and 2 designate units arranged in columns, one upon the other, and 3 and 4 are units arranged side by side with the units 1, 2 and secured thereto, the drawer being removed from the unit 4. 60

Each of the units is formed of sheet metal and comprises a frame including lengthwise angleiron bars 5 located at the four corners thereof, vertical side strips 6 and 7 at the front and rear ends of the angle iron bars 5, a top plate 8 and front and rear cross-strips 9, 10 connecting the lower ends of the strips 6, 7, all the parts of the frame being secured together in any suitable manner, as by spot welding. The angleiron 70 bars 5 are arranged with their flanges in vertical and horizontal positions and form guides for the sheet metal drawers 11, which may be of any suitable construction.

The rear cross-strip 10 of each unit is in 75 the form of an angleiron having one flange arranged in horizontal position and extending forwardly and resting at its ends on the horizontal flanges of the lower bars 5, said cross-strip having its other flange 12 80 extending upwardly and vertically and having portions, as its end portions, split to form tongues 13 which are bent rearwardly, downwardly and forwardly into a position opposed to the underside of the horizontal 85 flange and thereby forming hooks, which face forwardly at opposite ends of the strip 10 and which are arranged to receive rear edges of the horizontal flange 5^a of the upper angleiron bar 5 of the next lower unit, as clearly seen in Fig. 4. The interlocking of 90 the hooks 13 with the flanges 5^a of the angleiron 5 is brought about by a forward sliding movement of the upper section 2 or 4 on the lower section 1 or 3. 95

This tongue 13 and the flange 5^a constitute means which interlock by a horizontal sliding movement of one unit relatively to the other to interlock one unit with the adjoining unit of the next tier. Each of 100 the side strips 6 at the front end of each unit is formed with an open ended slot or notch, and a tongue at its opposite ends, the notch or slot 14 being shown as formed in the upper end of each side strip and the 105 tongue 15 as depending from the lower end. The tongue 15 is arranged to be brought into alignment with the slot 14 of the unit of the next tier as the next lower unit by a vertical movement of the front end of 110

the upper unit after the hooks 13 have been interlocked with the flanges 5^a. The lugs 15 and slots 14 constitute means which interlock by a vertical movement of one section relatively to the other to lock one unit against horizontal displacement relatively to the adjoining unit of the next tier.

- Each strip 7 at the rear end of one side of each unit is formed with an open-ended slot 16 opening through the rear edge of said strip while the strip 7 on the other side of the unit, or the opposing side of the next unit, is formed with an offset tongue 17 having a transverse portion 18 for entering the open end of the slot and a flange portion 19 for engaging the inner side of the strip 7 provided with the slot or notch 16 the tongue 17 being arranged to enter its transverse portion 18 into the slot by a forward movement of the unit, which forward movement may also engage the hooks 13 with the flange 5^a of the unit of the next tier. The slots 16 and offset tongues 17 constitute means which interlock by a forward sliding movement of one unit which means locks with the adjoining unit in the next column but in the same tier.

- Each strip 6 on one side of each unit is also formed with a slot 20 and offset tongue 21, while the strip 6 on the other side of the unit, or on the opposing side of the next unit, is formed with a slot 22 and an offset tongue 23. The offset tongue 21 projects from the bottom of one slot 20 while the tongue 23 on the opposing side projects from the top of the slot 22 in said opposing side. Hence, the tongues 21 and 23 are complementary to each other, and during vertical movement of the front end of one unit, as the upper unit, the tongue 23 will enter the slot 20 and the tongue 21 will enter the slot 22 and hence the tongues 21 and 23 will interlock during the vertical movement, which vertical movement will bring the lug 15 of the same unit into the slot 14 of the unit of the next lower tier. The offset tongues 21 and 23 constitute means which interlock during the vertical movement of one unit to lock each unit with the next unit in the same tier.

- In operation, the lowermost units are placed upon a suitable base and may be attached thereto in any suitable manner, or by means similar to the hooks 13 and the notches and the tongues 14, 15. The unit 2 is then placed on the unit 1 and the hooks 13 interlocked with the flanges 5^a and the lugs 15 interlocked with the slots 14 of the unit 1, by a successive forward movement of the unit and vertical movement of the front end of the unit 2. The unit 3 is placed beside the unit 1 and tongue 17 at the rear end thereof interlocked with the notch 16 of the unit 1 and the tongues 21 and 23 at the front ends of the units interlocked by the suc-

sive horizontal movement of the section 3 and the vertical movement of the front end thereof. The section 4 is then placed on the section 3 and the hooks 13 thereof are interlocked with the flange 5^a of the section 3, 70 and the tongue 17 interlocked with the slots 16 of the section 2 by a forward sliding movement of the section 4 and the section 4 is interlocked at its front end with the section 3 and with the section 2 by the vertical 75 movement of the front end of the section 4.

What I claim is:—

1. A sectional cabinet including units arranged to be placed one upon the other in columns and side by side in tiers, each unit having means for interlocking with the unit of the next tier of the same column and with the unit of the same tier in the next column by a sliding movement in a horizontal direction, and each unit also having 80 additional means for interlocking by a vertical movement with the adjacent unit in the next column and in the same tier, substantially as and for the purpose described. 85

2. A sectional cabinet comprising units, 90 each including a frame comprising a cross-bar in the form of an angleiron arranged with its flanges in vertical and horizontal position, the vertical flange extending upwardly and being formed with a tongue 95 struck therefrom and bent downwardly, rearwardly and forwardly into a position under and opposed to the horizontal flange, and each unit being formed with means at the rear end of its top for receiving the hook of the next upper unit, substantially as and for the purpose described. 100

3. A sectional cabinet comprising units, 105 each unit including a frame comprising lengthwise bars at its upper corners and a transverse bar at the lower rear end of the frame, the bar being in the form of an angleiron arranged with one flange thereof in horizontal position and extending forwardly and the other in vertical position and extending upwardly, the vertical flange having tongues struck therefrom and bent rearwardly, downwardly and forwardly into a position under and opposed to the horizontal flange, thereby forming hooks for hooking 110 over the rear ends of the bars of the adjoining unit, by a forward movement of the unit provided with the hooks, substantially as and for the purpose specified. 115

4. A sheet metal sectional cabinet comprising units, each unit including a frame having lengthwise angleiron bars at its corners, upright strips at their vertical front corners, a top plate and a crossbar at the lower or rear end of each unit, the cross strip being in the form of an angleiron mounted on the rear ends of the two lower lengthwise angleiron bars and having one flange extended forwardly and horizontally 125 and the other upwardly and vertically, the 130

vertical flange having tongues struck therefrom which are bent rearwardly, downwardly and forwardly into a position under and opposed to the horizontal flange forming hooks, for interlocking with the rear ends of the upper lengthwise angleiron bars of the adjoining unit, and each vertical strip at the front end of each unit having a notch and tongue at its opposite ends respectively, the notch of the strip of one unit being arranged to receive the tongue of the corresponding strip of the next unit when the hooks and flanges of the units are interlocked by a horizontal movement of one of the units, substantially as and for the purpose described.

5. A sectional cabinet including units arranged to be placed side by side, the units having means on their side faces arranged 20 to be brought into interlocking engagement by a horizontal sliding movement of one section, the portion of said means on each section which coacts with the other section projecting into the plane of the side wall of 25 the other section, and means arranged to be brought into interlocking engagement by a vertical movement of one section after the former means have been interlocked, substantially as and for the purpose set forth.

30 6. A sectional filing cabinet comprising units arranged to be located side by side, each unit having an open-ended slot at the rear end of one of its side walls, and the other having an offset tongue including a trans- 35 verse and a vertical portion arranged to enter the slot by a forward movement and interlock with the portion of the side wall provided with said slot, substantially as and for the purpose described.

40 7. A sectional cabinet comprising units arranged to be located side by side, the units having oppositely arranged tongues on their opposing sides arranged to interlock by a vertical movement of one of the 45 units the tongues on each of said opposing sides being offset therefrom and projecting into the plane of the other of said opposing sides whereby the sides lie flatwise against each other when the tongues are interlocked, substantially as and for the purpose specified.

50 8. A sectional cabinet comprising units designed to be placed side by side, one unit having an open-ended slot in one side and

at the rear end thereof, and the other having an offset tongue at its rear end including a transverse and a vertical portion, and the units having slots in their opposing sides near their front ends, and oppositely disposed offset vertical tongues, the tongue of one unit projecting upwardly from the lower end of its slot and the tongue of the other unit projecting downwardly from the upper end of the slot in such other unit, the slot and tongue at the rear ends of the units interlocking by a forward movement of one of the units and the offset tongue interlocking by a vertical movement of the front end of one of the units after the tongue and slot at the rear ends of the units have been interlocked, substantially as and for the purpose described.

9. A sectional filing cabinet including units designed to be mounted one upon the other and side by side, the units of each tier having means which interlock with the unit of the next tier by a horizontal sliding movement, and the units of each tier having means which interlock with the adjoining unit of the same tier by the horizontal sliding movement which interlocks the first mentioned means of the units, substantially as and for the purpose specified.

10. A sectional cabinet including units arranged to be placed one upon the other in 85 columns and to be placed side by side in tiers, each unit having means at one end for interlocking with the unit of the next tier and with the unit in the next column and in the same tier by a forward sliding 90 movement, and means at its other end for interlocking with the adjacent unit of the same column and in the next tier, and means for interlocking with the unit in the next column, but in the same tier, by a vertical 95 movement of the said other end of the unit after the interlocking means at the rear ends of the units have been engaged, substantially as and for the purpose set forth.

In testimony whereof I have hereunto signed my name, in the presence of two attesting witnesses, at Syracuse, in the county of Onondaga, in the State of New York, this 22nd day of May, 1914.

EVERETT STUCK.
